UNITED STATES PATENT OFFICE

157,938

GOOGLE FRAME

Charles Castelli, Union City, N. J., assignor to
Columbia Protekosit Co. Inc., Carlstadt, N. J.,
a corporation of New Jersey

Application July 1, 1948, Serial No. 147,321

Term of patent 7 years

(Cl. D57—1)

To all whom it may concern:

Be it known that I, Charles Castelli, a citizen of the United States, and resident of Union City, in the county of Hudson, State of New Jersey, have invented a new, original, and ornamental Design for a Goggle Frame, of which the following is a specification, reference being had to the accompanying drawing, forming a part thereof, and of which

Fig. 1 is a front view of a goggle frame, showing my new design.

Figs. 2, 3 and 4 are top, side and rear views, respectively, thereof.

I claim:

The ornamental design for a goggle frame, as shown.

CHARLES CASTELLI.
